UNITED STATES PATENT OFFICE.

FRED S. CARR, OF NEWTON, MASSACHUSETTS, ASSIGNOR, BY MESNE ASSIGNMENTS,
TO CARR FASTENER COMPANY, A CORPORATION OF MASSACHUSETTS.

SEPARABLE FASTENER.

Application filed January 7, 1927. Serial No. 159,692.

My invention aims to provide improvements in separable fasteners of the stud and socket type.

In the drawings, which illustrate a preferred embodiment of my invention:

Figure 1 is a rear elevation of the complete socket member as it appears when secured to a socket-carrying medium;

Fig. 2 is a vertical section showing the complete stud and socket installation, the stud being shown in elevation and the section of the socket being taken on the line 2—2 of Fig. 1;

Fig. 3 is an elevation of the socket-casing showing the stud-engaging spring assembled therewith;

Fig. 4 is a section taken on the line 4—4 of Fig. 1; and

Fig. 5 is a section taken on the line 5—5 of Fig. 1.

Referring to the embodiment of my invention illustrated by the drawings, I have shown, for the purpose of illustration, a three-side lock fastener which includes the usual type of stud 1, here shown as secured to a rigid support 2, and a novel form of socket A.

The socket installation includes the casing 3, containing the spring 4, which is secured to a flexible carrying medium 5 by means of the prongs 6 clinched against a back plate 7. The casing 3 is formed from a single piece of metal and is located at the front face of the carrying medium 5, while the back plate 7 is located at the opposite face of the carrying medium as shown in Fig. 2. Both the casing and the back plate are aligned with an aperture 8 through the carrying medium so that the stud may pass through the aperture 9 in the back plate and through the aperture 8, to engage the spring 4 in the casing.

At the back face of the casing 3, which lies against the carrying medium 5 (Fig. 2), I have provided, adjacent its periphery, a substantially continuous support-engaging portion B which is formed by bending inwardly, from the periphery of the casing, a plurality of portions C of various lengths and formations, as best shown in Fig. 3. The short portions 9^a are curved inwardly and downwardly (Fig. 4) and provide means for positioning the spring 4 in the casing. Other portions 10 extend inwardly

from the edge of the casing, in a direction generally parallel with the front face 11 of the casing and overlie the spring to hold it in assembly with the casing and further to prevent distortion of the spring. Still other portions 12 extend inwardly to the inner periphery of the portion B (Fig. 5) and then extend at right angles from the casing to provide the prongs 6. The remainder of the casing 3 is in the usual form, being provided with an aperture through which the head 13 of the stud 1 may project and which is intersected by the jaw portions 14 of the spring 4, as shown in Figs. 2 and 3.

The back plate 7 is of the usual form, having the elongated aperture 9, which is surrounded by the wall 15 closely fitting the shank 16 of the stud at three sides, to provide the means for preventing separation of the socket from the stud by stresses exerted thereon, except a pull adjacent to the lower edge.

When assembling the socket casing 3, to the carrying medium 5, the prongs 6 are forced through the carrying medium and enter slots 17 (Fig. 1) in the back plate 7 and are then clinched against the back plate 7. When thus secured, that portion of the carrying medium between the back plate 7 and the portion B of the casing is gripped firmly, so that, when stress is exerted upon the carrying medium in a lateral direction or toward the casing 3, there can be no tearing of the carrying medium adjacent the prongs or on the edge of the casing, as has been true of other known types of casings. The substantially continuous support-engaging portion B presents a smooth surface for the carrying medium to pull against and also provides an area between the prongs and the edge of the casing, against which the carrying medium may be firmly pressed.

The importance of spacing the prongs 6 from the edge of the casing, and the provision of the annular portion B is particularly brought out when used in connection with three-side lock fasteners, as compared with ordinary snap fasteners, which may be separated from any side. In a three-side lock fastener installation, the stresses exerted upon the carrying medium at three sides of the fastener where it can not be separated would, in many instances, be sufficient to

separate the ordinary snap fastener and prevent, to some extent, tearing or cutting the carrying medium. When the stress must be borne by the carrying medium, as in three-
5 side lock fasteners, the result has been a tearing or cutting of the carrying medium which produced an unsightly appearance and in most cases weakened the attachment of the socket to its carrying medium. To
10 prevent this, a practice has been formed of providing the casing with an extra plate, which would project beyond the casing.

Applicant's casing, as described and illustrated, eliminates the use of the extra plate
15 and provides the advantages of having an annular portion outside the prongs for the purposes described and at the same time provides for a neat, durable, less expensive fastener installation.

20 My invention is not limited to the particular embodiment illustrated and described.

I claim:

1. A fastener socket comprising a casing provided with a substantially continuous support-engaging back face portion of substantial width formed by a series of closely abutting inwardly bent portions extending inwardly from the periphery of the casing, a plurality of attaching prongs extending at right angles to the casing and located adjacent to the inner edge of said support-engaging portion and a spring held in assembled relation with said casing by some of said inwardly bent portions.

35 2. A fastener socket comprising a casing having a substantially continuous support-engaging back face portion formed by a series of closely abutting portions bent inwardly from the periphery of the casing and a stud-engaging spring positioned in said casing against the inner ends of some of said inwardly bent portions and held in said casing by some of the other of said portions.

45 3. A fastener socket comprising a casing having a substantially continuous support-engaging back face portion formed by a series of closely abutting portions bent inwardly from the periphery of the casing and a stud-engaging spring positioned in
50 said casing against the free ends of some of said inwardly bent portions, other portions being extended to provide attaching means for securing the casing to its carrying medium and still other portions extending over
55 said spring to hold it in assembled relation

with said casing and at the same time back-support said spring.

4. A fastener socket comprising the casing A provided at its inner face with the substantially continuous marginal portion B of substantial width formed by a series of closely abutting inwardly bent portions extending inwardly from the periphery of the casing, said marginal closely abutting portion being divided into the portions 12, 9^a 60 and 10, said portions 12 having integral with their ends the prongs 6 and a spring 4 held in assembly with the casing A by the portions 9^a and 10.

5. A fastener socket installation comprising, in combination, a stud-receiving socket member having means for engagement with a cooperating stud, a carrying medium and an attaching plate, said stud-receiving socket member being provided with a plurality of relatively closely abutting inwardly bent portions extending from the periphery of the casing to provide a relatively wide substantially continuous carrying medium engaging surface and attaching 75 prongs located at the inner edge of said carrying medium engaging surface, said attaching prongs securing the attaching plate and stud-receiving socket member against opposite sides of the carrying medium to grip a portion thereof tightly between the carrying medium engaging surface of the socket member and the attaching plate.

6. A fastener socket installation comprising, in combination, a casing element, a carrying medium and an attaching plate, said casing element being provided with a plurality of relatively closely abutting inwardly bent portions extending from the periphery of the casing to provide a substantially continuous carrying medium-engaging surface, means for securing the attaching plate and casing against opposite sides of the carrying medium to grip a portion thereof tightly between the inwardly bent portions of the casing and the attaching plate and a spring positioned in said casing against the ends of some of said inwardly bent portions so that the spring is free from the gripping action exerted between 100 the inwardly bent portions and the attaching plate.

In testimony whereof, I have signed my name to this specification.

FRED S. CARR.

CERTIFICATE OF CORRECTION.

Patent No. 1,711,454.

Granted April 30, 1929, to

FRED S. CARR.

It is hereby certified that error appears in the printed specification of the above numbered patent requiring correction as follows: Page 2, line 64, claim 4, strike out the words "closely abutting" and insert the same before the word "portions" in line 65; and that the said Letters Patent should be read with this correction therein that the same may conform to the record of the case in the Patent Office.

Signed and sealed this 18th day of June, A. D. 1929.

(Seal)

M. J. Moore,
Acting Commissioner of Patents.
